R. GLAZNER

GASOLINE RESERVE DEVICE

Filed Sept. 28, 1924

INVENTOR

R. GLAZNER

BY

Wm. W. Leo.

ATTORNEYS

UNITED STATES PATENT OFFICE.

RAYMOND GLAZNER, OF SEGUIN, TEXAS.

GASOLINE-RESERVE DEVICE.

Application filed September 29, 1924. Serial No. 740,621.

To all whom it may concern:

Be it known that I, RAYMOND GLAZNER, a citizen of the United States, and a resident of Seguin, county of Guadalupe, State of Texas, have invented a new and useful Improvement in Gasoline-Reserve Devices, of which the following is a full, clear, and exact description.

My invention relates to improvements in gasoline reserve devices, and it consists in the combinations, constructions, and arrangements herein described and claimed.

An object of my invention is to provide a gasoline reserve device which may be regulated so as to retain a portion of gasoline for emergency purposes, and which also may be locked in closed position so as to prevent any gasoline being drained therefrom unless the person has the right key to unlock the device.

A further object of my invention is to provide a device of the type described which may be applied to any standard gasoline tank and which does not take up any additional space than that which is occupied by the tank itself.

A further object of my invention is to provide a device of the type described which has manually controlled means for operating the device so as to draw from the reserve supply of gasoline in case the driver of the car needs a supply.

A further object of my invention is to provide a device of the type described which is simple in construction, durable, and efficient for the purpose intended, and which may be readily attached to any gasoline tank.

Other objects and advantages will appear in the following specification, and the novel features of the invention will be particularly pointed out in the appended claims.

My invention is illustrated in the accompanying drawings, forming part of this application, in which

Figure 1 shows a vertical section through the device as operatively applied to a gasoline tank, portions thereof being shown in elevation,

Figure 2 is a top plan view of the device, Figure 3 is a section along the line 3—3 of Figure 2,

Figures 4 and 5 are sections along the lines 4—4 and 5—5 of Figure 1, and

Figure 6 is a section along the line 6—6 of Figure 2.

In carrying out my invention I make use of a gasoline tank 1 which is provided with the ordinary filler cap 2 and an outlet pipe 3. In the present form of the invention I have shown the device as being operatively applied to a gasoline tank that is used in Ford cars. It is obvious, however, that the device may be used in various makes of tanks without departing from the spirit and scope of my invention. The pipe 3 in Figure 1 is in reality the upper portion of a sediment bulb which is the usual equipment of Ford cars.

The device comprises a tube 4 which is screwed onto the upper part of the sediment bulb 3 at 5. A lock 6 of any standard make is screwed into the top of the pipe 4 and has a portion 7 which projects above the top wall 8 of the tank 1. The portion 7 is threaded at 9 and receives a lock nut 10 which bears against the outer surface of a plate 27 and clamps the lock to the wall. The lock 6 when secured in position by means of the nut 10 also secures the upper end of the pipe 4 in position. The pipe or tube 4 is therefore held at each end and as shown in Figure 1 extends between the top and bottom walls of the tank 1.

In Figure 6 I have shown the opening 11 through which the portion 7 extends. The portion 7 is adapted to be inserted through the opening 11 and then to be turned with respect to the wall 8 so as to permit the actuating handle 12 hereinafter more particularly described, to extend to the front of the tank 1, where it may be manually operated. A washer 13 having a corrugated under side is carried by the plate 27 and is pressed down against the outer surface of the wall 8 so as to close the opening 11 and to make a liquid-tight joint at this point. The nut 10 when screwed down upon the plate 27 locks the washer 13 in place, and not only causes the washer to make a liquid-tight joint, but locks the plate 27 against movement with respect to the tank.

The means for operating the device is

clearly shown in Figures 1 to 3 inclusive. A valve 14 is rotatably disposed in the lower end of the tube 4 and has two openings 15 and 16 which are spaced ninety degrees apart. The tube 4 has two openings 17 and 18 which are disposed in vertical alignment, and which are adapted to register with the openings 15 and 16 respectively. When the valve 14 is turned, the opening 15 will first register with the opening 17. After the valve has been turned an additional ninety degrees, the opening 16 will register with the opening 18. The means for rotating the valve 14 consists in a rod 19 that is connected 15 to the rotating portion 20 of the lock 6. The lock 6 is turned by means of a key 21 in the same manner as the standard lock. The sleeve 22 is rotatably mounted upon a portion 7 and has a slot 23 that is adapted to be 20 aligned with the key hole of the lock 6. The sleeve 22 has a gear 24 thereon which is in mesh with a rack 25. The rack in turn is slidably carried by guides 26 which in turn are supported by the plate 27. The plate 27 25 is fastened to the wall 8 by means of the washer 13.

In Figure 2 I have shown the rack 25 as being provided with an actuating handle 12 at its free end.

30 The rack 25 is adapted to be moved into three positions so as to close the valve 14 and then to bring the openings 15 and 17 into alignment, and then the openings 16 and 18 into alignment. Figure 4 shows the valve 35 in closed position, Figure 1 shows the valve in its second position, i. e., with the openings 15 and 17 in alignment, and Figure 5 shows the valve in third position, i. e., when the openings 16 and 18 are in alignment. 40 The sleeve 22 is held in place upon the portion 7 by means of a bracket 29. The key 21 is merely for the purpose of connecting the sleeve 22 with the lock 6, so that any rotation of the sleeve 22 which is caused 45 by the rack 25 will also turn the lock 6, and thus actuate the valve 14. The driver knows when the rack 25 is in its various positions due to the fact that the leaf spring 30 enters notches 31 in the under side of the rack 25 50 and yieldingly holds the rack against further movement, as soon as it enters any one of these notches.

From the foregoing description of the 55 various parts of the device, the operation thereof may be readily understood. When the handle 12 is in its outermost position, the openings 16 and 18 are in alignment and the device is drawing from the reserve supply of gasoline. If the handle 12 be pushed 60 in a slight distance so as to cause the leaf spring 30 to enter the second notch 31, the openings 15 and 17 will be aligned, and the device will now be drawing gasoline from a point above the reserve supply point, and 65 a still further movement of the handle 12

inwardly, will swing both of the openings 15 and 16 out of alignment with the openings 17 and 18, and thus prevent any gasoline from flowing through the openings 17 and 18 and into the pipe 3.

70 When the driver wishes to lock his car, he merely has to move the handle 12 into its innermost position and then remove the key 21 from the lock 6. The handle 12 may now be actuated in the manner heretofore described, but will merely rotate the sleeve 22 due to the fact that the sleeve and lock have been disconnected from each other by the key 21. The key in reality is a connecting link between the handle 12 and the 75 valve 14. It is necessary to have the right key before the lock 12 can be rotated so as to actuate the valve 14. The key can only be inserted into the lock 6 when the valve 14 is in closed position, and therefore if the 80 driver upon entering his car wishes to again place the gasoline in the tank in connection with the pipe 3, he must push the handle 12 to its innermost position. The key 21 can now be inserted and will connect the sleeve 22 to the lock 6 in the manner heretofore 85 described. The device can now be actuated in the ordinary manner. The handle 12 is not moved into its outermost position unless the reserve supply of gasoline is needed.

90 The device is simply constructed, and may be quickly attached to a gasoline tank with but slight alterations being necessary in the latter.

95 I claim:

100 1. The combination with a gasoline tank, a valve for controlling the flow of gasoline from said tank, a lock having the barrel thereof operatively connected to said valve, a key adapted to rotate the barrel of said lock so as to actuate said valve, said valve being adapted to be swung into three positions, and manually operated means for swinging the barrel of said lock, said key connecting said manually operated means 105 with said barrel, said manually controlled means comprising a gear loosely mounted upon said lock, a rack for rotating said gear, said key being adapted to connect the barrel 110 of said lock to said gear.

115 2. The combination with a gasoline tank, a tube carried by said tank, said tube having openings therein, a valve disposed in said tube and having openings adapted to be aligned with the openings in said tube, a lock carried by said tube, the barrel of said lock being operatively connected to said valve, a gear loosely mounted on said lock and having a slot therein adapted to register with the key hole in said lock, a rack for actuating said gear, said valve being adapted to be swung into three positions, means for yieldingly holding said rack in three positions, and a key for connecting said gear to the barrel of said lock.

3. In a device of the type described a valve, means for actuating said valve, means covering said first named means so as to prevent the operation of said first named means, removable means adapted to connect said first and said second named means together, and manually controlled means for actuating said cover means, said cover means being adapted to be moved by said manually controlled means without moving said valve 10 actuating means unless said removable means connects said cover means with said valve actuating means.

RAYMOND GLAZNER.
